CLAIM

The ornamental design for a handle with stylized skillet cutout, as shown and described.

DESCRIPTION

FIG. 1 is an enlarged front perspective view of a handle with stylized skillet cutout showing my new design, which is identical to the rear perspective view thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, shown in the full environment from which the enlarged views are taken. The broken lines in the drawings indicate environment and do not form a part of the claimed design.

1 Claim, 6 Drawing Sheets
